UNITED STATES PATENT OFFICE

RICHARD SPRY, OF PORT ALFRED, QUEBEC, CANADA

METHOD OF SPLICING PAPER CORES, TUBES, AND THE LIKE

Application filed April 26, 1930. Serial No. 447,619.

This present invention relates to certain new and useful improvements in the method of splicing paper cores, tubes and the like.

The primary object of the invention resides in the provision of the method of splicing paper cores, tubes and the like, whereby a great saving may be effected in paper mills and other establishments where a large number of short length paper cores, tubes and the like are now discarded.

Another object of the invention resides in the provision of the method of splicing paper cores, tubes and the like, whereby a considerable number of paper cores, tubes and the like now discarded may be redeemed and employed as full length cores, tubes and the like.

A further object of the invention resides in the provision of the method of splicing paper cores, tubes and the like, whereby the desired length of core, tube or the like may be readily produced from a number of shorter sections firmly spliced together.

A still further object of the invention resides in the provision of the method of splicing paper cores, tubes and the like, whereby the sections may be readily spliced and firmly connected at the minimum cost and expenditure of time and labour.

A still further object of the invention resides in the provision of the method of splicing paper cores, tubes and the like in a simple and efficient manner and without waste of time or material and without decreasing the length of the sections by cutting off the opposing ends of the sections to be connected.

A still further object of the invention resides in the provision of the method of splicing paper cores, tubes and the like, without requiring an expensive and complicated machine, tools or other mechanism and skilled workmen for redeeming and splicing together odd and discarded sections of paper cores, tubes and the like.

To the accomplishment of these and related objects as shall become apparent as the description proceeds, my invention resides in the construction, combination and arrangement of parts as shall be hereinafter more fully described, illustrated in the accompany-

ing drawings and pointed out in the claims hereunto appended.

The invention will be best understood and can be more clearly described when reference is had to the drawings forming a part of this disclosure, wherein like characters indicate like parts throughout the several views.

In the drawings:—

Figure 1 is perspective view of the opposed ends of two paper core sections prepared for splicing and the splicing band interposed between said ends, ready for splicing together the sections;

Figure 2 is a longitudinal section through the spliced sections and the splicing band secured thereon;

Figure 3 is a view similar to Figure 1, showing a modified form of the invention employing the adjustable transversely split splicing band;

Figure 4 is an elevation of the spliced sections with the splicing band thereon; and

Figure 5 is a fragmentary transverse section, taken substantially on the plane of line 5—5 of Figure 4, looking in the direction indicated by the arrows.

Referring more in detail to the drawings, it is to be noted that the core or tube sections 11 to be spliced together have their opposed ends 12 which are to be connected reduced in their exterior diameter as by squeezing or compressing the ends when the cores or tubes are formed of paper, a composition or other material which will permit such compression, or by cutting away a portion of the material on the outer face when said cores or tubes are formed of metal or similar material which cannot be reduced in its exterior diameter by compression. A series of inwardly directed pockets 13 are then provided in the reduced ends 12, leaving between said pockets 13 a corresponding number of arcuate extensions 14 with their longitudinal walls serving also as the longitudinal walls

of the pockets 13 and lying in planes radially of the cores or tubes as well as longitudinally thereof. As the opposed ends of the cores or tubes 11 are similarly cut, the arcuate extensions 14 of each of said tubes 11 will fit in the pockets 13 of the other sec-

tion 11. The pockets 13 are of such a depth as to determine a short distance outwardly of the main or non-reduced portion of the cores or tubes 11, thus presenting reduced ends 12 of a greater length than the pockets 13 and the arcuate extensions 14. A splicing band 15 is employed which fits snugly over the reduced ends 12 of the core or tube sections 11, completely covering the arcuate extension 14 as well as the pockets 13. In assembling the sections 11 in this manner, the outer face of the reduced ends 12 and the walls of the pockets 13 and arcuate extensions 14, should be coated with glue or the like, except on the inner face of the core or tube sections 11. The inner face of the continuous band 15 should also be coated with glue or the like and this band then forced onto the reduced end 12 of one of the core or tube sections 11. The reduced end 12 of the other core or tube section 11, should then be forced into the continuous band 15 and turned in such a manner as to permit the arcuate extensions 14 to move into the pockets 13 of the first core or tube section 11, thus firmly uniting the core or tube sections 11 with the outer face of the continuous band 15 flush with the outer face of the said core or tube sections 11. When the glue has thoroughly hardened and set, the core or tube sections 11 will be permanently spliced together and the complete core or tube of the required length thus completed from the waste or discarded core or tube sections 11.

In the modified form disclosed in Figures 3 to 5 inclusive, a transversely split splicing band 16 is employed in place of the continuous band 15. This split band 16 has a series of teeth 17 bent inwardly from one wall 18 of the transverse split thereof for engagement between the opposed longitudinal walls of adjacent or interlocking arcuate extensions 14 of the assembled core or tube sections 11, while a tongue 19 is provided on the opposite wall 20 of the transverse split, with side wings 21 on the tongue 19. This second end of the transversely split band 16 is adapted to overlap the first end and permit the side wings 21 of the tongue 19 to be extended through the parallel slits 22 in the band 16, adjacent the first mentioned end thereof, as the band 16 is tightened around the reduced ends 12 of the core or tube sections 11, after connection of the core or tube sections 11 with one another and interlocking of the arcuate extensions 14 of the core or tube sections 11 and the pockets 13 thereof. The band 16 is also securely fastened in position on the reduced core ends 12, as it is tightened therearound. This is readily accomplished by rotating the assembled cores or tubes 11 with the band 16 thereon between three or more rollers, one of which is provided with circumferential series of spaced teeth which serve to punch inwardly through the band

16, and thus punch out from the band 16, circumferential series of pointed projections 23 which bite into the reduced core ends 12, while rotating the band 16 in proper direction to tighten and securely fasten the band 16 on the interlocked reduced ends 12 of the core or tube sections 11 to which it has been applied. In this form, it is not necessary to employ glue or similar means to unite and hold together the interlocked reduced ends 12 of the core or tube sections 11.

As the construction of the device has thus been described in detail, brief reference is now had to its use and modus operandi: Any desired length of core or tube may be produced from waste sections of odd lengths by reducing and cutting one end of each of the sections to provide the pockets 13 and arcuate extensions 14 thereon and then connecting the sections by means of the band 15 or the band 16, in the manner previously set forth. In either form, the band 15 or 16 has its outer face flush with the core or tube sections which it serves to unite and hold together. It is also apparent that turning of one of the sections, independently of the other is prevented by the interlocking of the arcuate extensions 14 of the two sections 11 as well as by the band 15 or 16. By selecting the proper sections 11 a core or tube of any predetermined length may be readily built up, without waste. Should it be found necessary to cut off a portion of one of the selected sections 11, this cut off portion may be spliced to another section, when required.

From the foregoing description, taken in connection with the accompanying drawings, it will be manifest that means for and method of splicing paper cores, tubes and the like, is provided that will fulfill all the necessary requirements of such a device, but as many changes could be made in the above description and many apparently widely different embodiments of my invention may be constructed within the scope of the appended claims without departing from the spirit or scope thereof, it is intended that all matters contained in the said accompanying specification and drawings, shall be interpreted as illustrative and not in a limited sense.

Having thus described my invention, what I claim as new and desire to secure by Letters Patent is:—

1. The method of splicing paper cores, tubes and the like including preparing opposed ends of core or tube sections for interlocking engagement; and applying a band over said ends.

2. The method of splicing paper cores, tubes and the like including the preparation of opposed ends of core or band sections for interlocking engagement; and applying a band over said ends with the outer face of said band flush with the outer face of the main portions of said sections.

3. The method of splicing paper cores, tubes and the like including the reduction of the exterior diameter of opposed ends of core or tube sections; interlocking said ends; and applying a band around said ends with the outer face of the band flush with the outer face of said sections.

5 4. The method of splicing paper cores, tubes and the like including reducing and recessing the ends of opposed core or tube sections; interlocking of said ends; and securing a band around said ends.

10 5. The method of splicing paper cores, tubes and the like including reducing the exterior diameter of opposed ends of core or tube sections; recessing a portion of the reduced ends and interlocking said ends; and securing a band around the reduced interlocked ends of said sections.

15 20 In testimony whereof I hereunto affix my signature.

RICHARD SPRY. [L. s.]
